FOLDING-MACHINE FOR COLLARS AND SIMILAR ARTICLES.

1,177,696.

Specification of Letters Patent.

Patented Apr. 4, 1916.

Application filed November 6, 1912. Serial No. 729,759.

To all whom it may concern:

Be it known that we, JOHN W. GARDNER and JOHN W. CONDON, citizens of the United States of America, and both residing at the city of Troy, in the county of Rensselaer and State of New York, have invented certain new and useful Improvements in Folding-Machines for Collars and Similar Articles, of which the following is 10 a specification.

Our invention relates to folding machines for collars and similar articles, and the object of our invention is to provide a device for folding collars, cuffs and similar articles in such a manner that the folding blades may be extended on a curve or segment of a circle, to the effect that when different lengths of the article are folded, their contour may be preserved whether 20 they are of shorter or longer size.

In folding machines as heretofore constructed, the folding blades are extended in a line parallel with the bed or support on which the collars are folded, the result being that shorter sizes have more spring than the longer ones, a defect which is overcome by our invention.

We have also provided means for moving the folding blades to conform to our invention and means for exerting pressure upon the article to be folded, and such other elements and combinations as are hereinafter set forth and claimed.

We accomplish these objects by means of the mechanism illustrated in the accompanying drawings, in which:

Figure 1 is a plan of our machine after the removal of the die. Fig. 2 is a front elevation of the bed of the machine with the die raised. Fig. 3 is a plan of the bed of the machine with the folding blades and die removed. Fig. 4 is a side elevation of our machine. Fig. 5 is an elevation of the side of the machine opposite that shown in 45 Fig. 4.

Similar letters refer to similar parts throughout the several views.

The bed, A, is mounted on a suitable frame, B, by means of bolts, C, or in any suitable manner. On the bed, A, we form the runways, a, b and c, into which reciprocate the arms, E, F, and G, respectively. The arm, E, is attached to or formed integral with the plate, H, and the arm, F, is 55 likewise formed in connection with the

plate, J, the arm, G, being part of the plate, K.

The runway, a, is at such an angle to the horizontal axis of the bed, A, that the plate, H, may be moved by the reciprocation of 60 the arm, E, toward the center of the bed, A, as well as toward the side opposite the said runway; and in the same manner, the runway, b, is arranged in reference to the plate, J. The runway, c, is substantially at 65 right angles to the axis of the bed, A. The plates, H and J, are curved and have their concave sides toward the axis of the bed; the plate, K, is also curved and has its convex side toward the axis of the bed. 70

On the plates, H, J and K, we adjustably secure the folding blades, L, N, O and Q, preferably by means of the bolts, f, r, p and q, passing through the elongated slots, g, g. We also secure to the plate, H, an extension 75 blade, M. This blade may be secured, as shown in the drawing, attached to the strip, m', by screws, m and n, which strip is also attached to the blade, L, by means of the rivets, o, o. The blade, M, preferably overlaps the plate, J, although is not attached to it. The blade, M, may be changed for another blade corresponding to the length and shape of the collar or article to be folded. 80

We also secure to the blade, Q, a plate, P, 85 which is substantially the same in its manner of mounting and construction as the blade, M. We do not wish to confine ourselves to this method of attaching the different blades to the plates, as it is evident that 90 other means may be adopted consistent with the invention.

It is also evident that the blades, M and P, may be omitted, in which case the blades, L and N, would be each in one piece, but lengthened and separate 95 blades used for each size of collar to be folded. Likewise the blades, O, P and Q, may be integral and interchangeable. The different lengths and extensions of the folding blades attached to the plates, H, J and K, are so formed that they always conform 100 to a segment of the circumference of a circle.

In order to move the plate, H, and therefore the folding blade attached to it, we 105 mount a bell crank lever, R, pivoted at s, and having one end hooked adapted to engage a projecting knob, S, on the arm, E. The other end of the bell crank lever is provided with a roller, T, adapted to engage 110

a cam disk, U, which is mounted on a shaft, W. When the raised portion, u, of the cam disk is brought by the rotation of the cam disk on the shaft, W, into contact with the roller, T, the bell crank lever, R, will move in such a manner as to cause the arm, E, to move toward the center of the bed, A. In the same way, the bell crank lever, 9, connected by knob, 10, with the arm, F, and having a roller 11, engaging the cam disk, 12, will move the plate, J, toward the center of the machine. A like bell crank lever, 13, connected with the knob, 14, and provided with a roller, 15, engaging the cam disk, 16, will move the plate, K, toward the center of the machine.

Near the rearward edge of the bed, A, we place the blocks, V, provided with bearings for the trunnions, X, on the curved head or block, Y, which carries the die, Z. An arm, y, is attached to the curved head, Y, forming, with the rest of the head, a bell crank lever mounted by the trunnions, X, in the blocks, V, to which arm, y, we attach the rod, v, which extends to one end of the foot lever, z', and provided with the foot pedal, x. The rod, v, also carries the weights, v'. By pressing the foot on the foot pedal, x, the rod, v, will be lifted and the die, Z, depressed and brought into contact with the collar on the bed, A.

In order to press down in position the folded portions of the collar we force the pressure plate, 20, upward against the die, Z, and blades, L, M, N, O, P and Q. This may be done by the mechanism illustrated more particularly in Fig. 4, although we do not wish to limit ourselves to this means of applying pressure to the folded article between the die and blades away from the bed.

The die, Z, may be made in separate portions to allow for extensions or contractions, or an entire die may be provided for each length of article to be folded, but when such extensions or contractions are made the edges of the die conform to the same segmentary extensions and contractions as the folding blades.

A shaft, 50, to which power is applied by means, shown conventionally in Fig. 5, carries a gear, 21, and is provided with a cam face, 22, which by the rotation of the gear engage a roller, 23, on a lever, 24, which lever is pivoted to the base of the frame. The lever, 24, has attached to it a rod, 25, which is connected with a block, 26, to which are pivoted at 27 the ends of the links, 28 and 29. The link, 28, is pivoted at 30, to the frame, B, of the machine. The link, 29, is connected with an arm 31, pivoted at 32, to the lower portion of the frame, B. The arm, 31, is connected with the rod, 33, which is attached to one end of a lever, 34, pivoted to the frame, B, at 35, and con-

nected with the rod, 36, which engages the pressure plate bracket, 37. As thus connected up when the cam, 22, engages the roller, 23, the rod, 24, presses the block, 27, and straightens out the toggle comprising links, 28, 29, thereby depressing the link, 31, and drawing downward the rod, 33, which presses upward the rod, 36, and therefore the pressure plate bracket, 37, passing upward through the bed A. The gear, 21, meshes with the gear, 38, which is suitably mounted on the shaft connected with the frame, B, the gear, 38, meshing with the gear, 39, which is keyed to the shaft, W, which carries the disks, u, 12 and 16. The inner edges of the folding blades, while in their outward position, conform to the perimeter of the die and form a matrix slightly larger than the die, conforming to the shape thereof.

The operation of the machine is as follows:—The blank to be folded is placed on the folding blades. The foot is placed on the pedal, x, which by means of the rod, v, and the swinging support, y, Y, causes the die to descend, passing the edges of the folding blades and upturning the edges of the blank between the edges of the die and the folding blades. A stop, not shown, on the swinging support of the die determines its position at the conclusion of its operation. The upturned edges of the blank hold it in position while the folding blades are caused to move inward by the action of the rotating disks, U, 12 and 16, thereby infolding the upturned edges of the blank over the die. A continuance of the operation of the machine brings the pressure plate upward and in contact with the underside of the blank held on the die, pressing the inturned edges of the die against the blades. A further continuance of the operation causes the pressure plate to descend, after which the folding blades are withdrawn and the die with the blank attached raises to its original position. The movements of the different elements of the machine are made automatic by means, not shown, but succeed each other and return to their original position when pressure is placed on the pedal, x.

What we claim as our invention and desire to secure by Letters Patent is:

1. In a machine for folding collar blanks and similar articles, a series of reciprocating plates; a series of blades curved along one edge; and means for adjustably securing said blades to said plates, permitting of the movement of the blades in the arc of a circle corresponding to and continuous with the segment of a circle formed by the curved line of said blades when in the extended position, whereby the length of said blades may be extended and the degree of curvature of the blades thus extended be preserved throughout the different lengths.

2. In a machine for folding collar blanks and the like, a series of curved folding blades; a series of plates; means for reciprocating said plates; means for adjustably securing said folding blades to said plates; and means for extending said folding blades in the direction of the arc of a circle.

3. A machine for folding collar blanks and similar articles, comprising a bed; runways formed therein; an arm adapted to reciprocate in each of said runways; a plate attached to each said arms; a series of curved folding blades provided with elongated curved slots therethrough; bolts secured to said plates and passing through said slots; an extension blade secured to one of said plates between two of said curved blades.

4. In a machine for folding collar blanks and similar articles; a die over the edges of

which the blank is folded; a series of folding blades curved along one edge; a series of sliding plates also curved along each edge; means for securing said blades to said plates, whereby the blades on said plates 25 may be moved in the direction of the arc of a circle corresponding to the direction of the curve of said curved edges when the circumference of the circle has been increased by the distance that the blades have 30 been moved; with means for exerting pressure on said die, blank and folding blades, substantially as described.

In testimony whereof we have affixed our signatures in presence of two witnesses.

JOHN W. GARDNER.

JOHN W. CONDON.
